ATTACHMENT FOR STAPLING MACHINES

John Thomas Dalton, Durham, N. C., assignor to
The American Tobacco Company, New York,
N. Y., a corporation of New Jersey

Application January 14, 1941, Serial No. 374,326

22 Claims. (Cl. 1-2)

This invention relates to attachments for wire stitchers or stapling machines and more particularly to an apparatus for securing a tag to one of the strings of a bag of the string closure type.

In my prior Patents Nos. 2,207,912, 2,207,913 and 2,207,914, granted July 16, 1940, I have disclosed and claimed several types of apparatus for securing a tag to the string of a bag of the string closure type. In these machines the tags are secured to the bag string before filling the bag and I provide means for feeding a tag to the anvil of the wire stitcher prior to each descent of the stitcher head, means for feeding a bag to the anvil and means for collecting the bags after the tags are secured to the strings.

In my copending application, Serial No. 339,960, filed June 11, 1940, I have disclosed and claimed an apparatus in which a tag is secured to one of the bag strings after the bag has been filled. This apparatus comprises tag feeding means generally similar to that disclosed in my prior patents whereby a tag is fed to the anvil prior to each descent of the stitcher head and is stitched to the bag string when the stitcher head descends.

The apparatus of the present application is an improvement over that disclosed in my copending application. As in the earlier forms of my machine, the present apparatus comprises a pair of reciprocating members to deliver the individual tags to the anvil. The present machine also includes an oscillating and reciprocating hook by means of which the string of a bag is carried over the anvil. The present machine is designed to apply the tags to the bag strings after the bags have been filled and is preferably assembled with a tobacco filling machine at the outlet end of the tobacco filling machine so that the bag, after filling and after application of the revenue stamp and labels, is fed directly to the stitcher head for the application of the tag to the bag string. The present invention is an improvement over the apparatus disclosed in my copending application in that I have simplified the construction of the machine and particularly the means for actuating the pair of reciprocating members which feed the tags to the anvil and the reciprocating and oscillating hook which carries the bag string over the anvil.

In the accompanying drawings I have shown one embodiment of the invention. In this showing:

Fig. 1 is a side elevation of the machine;
Fig. 2 is an end view from the left in Fig. 1 showing the drive means;

Fig. 3 is an end view from the opposite end of the machine showing the stitcher head;

Fig. 4 is a horizontal, sectional view substantially on line 4-4 of Fig. 1;

Fig. 5 is a horizontal, sectional view substantially in the same plane as Fig. 4 showing certain of the parts on an enlarged scale;

Fig. 6 is a vertical, sectional view on line 6-6 of Fig. 5;

Fig. 7 is an enlarged, detailed, sectional view of the spider which forms a part of the means for feeding the tags to the anvil;

Fig. 8 is a front elevation of one of the pairs of tag gripping jaws of the spider shown in Fig. 7;

Fig. 9 is a side elevation of the mechanism by which the tags are fed from a tube to the spider;

Fig. 10 is a plan view of one of the gripping jaws of the tag feeding mechanism shown in Fig. 9;

Fig. 11 is a plan view of the end of a reciprocating member to which the jaw shown in Fig. 10 is secured;

Fig. 12 is an end elevation of the gripping jaw shown in Fig. 10;

Fig. 13 is a plan view of the other gripping jaw;

Fig. 14 is an enlarged elevation of the gripping mechanism shown in Fig. 9, the jaws being shown in closed position in Fig. 14 and in open position in Fig. 9;

Fig. 15 is a detailed, sectional view substantially on line 15-15 of Fig. 5 showing a portion of the mechanism for guiding the string to the anvil;

Fig. 16 is a similar view on line 16-16 of Fig. 5 showing a string tensioning device;

Fig. 17 is a side elevation of the lower end of the tag tube;

Fig. 18 is a front elevation thereof;

Fig. 19 is a detailed view showing the lower end of the tube in section, and showing a surrounding collar in elevation, the sections of the tube and collar being taken in separate planes;

Fig. 20 is a rear elevation of the lower end of the tag tube;

Fig. 21 is an enlarged view of a tag showing the string stitched thereto;

Fig. 22 is a vertical, sectional view on line 22 of Fig. 19 looking in the direction of the arrows; and

Fig. 23 is a similar view on line 23-23 looking in the direction of the arrows.

The frame of the machine, which may be in a single casting, comprises a base or bed plate 2, end walls 4 and 6, and a rear wall 8. The end wall 6 terminates above the base as at 10 to per-

mit certain of the movable parts to extend beyond this end wall.

A main shaft 12 is mounted in suitable bearings in the end walls 4 and 6 and this shaft carries a drive sprocket 14 which is loosely mounted on the shaft and is adapted to receive a drive chain 16 (see Fig. 2) by means of which the apparatus is driven from any suitable source of power, such as a shaft of the tobacco filling machine with which it is adapted to be used. A drive gear 18 is mounted on shaft 12 adjacent the sprocket 14 and the sprocket 14 and the gear 18 are provided with openings which may be aligned for the reception of a pin 20 to lock the sprocket to the shaft and drive the machine. In normal operation the pin 20 is retained in locked position by means of a spring 22 carried on the hub 24 of gear 18. Shaft 12 is provided with a hand wheel 26 so that by removing the pin 20 from the opening in the sprocket 14, the machine may be disconnected from its source of power and driven by hand.

A cam shaft 28 is arranged above the main shaft 12 and is also mounted in suitable bearings in the end plates 4 and 6. This shaft is provided with a gear 30 (see Figs. 1 and 2) which meshes with the gear 18 to drive the cam shaft from the main shaft. This shaft is provided with cams 32 and 34 by means of which the pair of reciprocating members are actuated to feed individual tags from the tube to the spider. The shaft is further provided with a pair of cams 36 and 38 which actuate the reciprocating and oscillating hook by means of which the bag string is guided over a tag on the anvil.

A shaft 40 is mounted in suitable bearing carried by brackets 42 beneath the bed plate of the machine and this shaft is driven from the main shaft 12 by a Geneva movement to impart a step by step motion to the spider which delivers the tags to the anvil of the wire stitcher. As shown in Fig. 2 a gear 44 is carried by a stub shaft 46 mounted in the end plate 4 and this gear meshes with a gear 48 on the drive shaft. Gear 44 also meshes with a gear 50 which is carried by another stub shaft 52 mounted in the end plate and which forms one element of the Geneva movement. Gear 50 is provided with a pin 54 which is adapted to be received successively in radial slots 56 of wheel 58 which is mounted on the shaft 40 and thereby impart a step by step movement to the shaft 40.

A stitching machine is shown in Figs. 1 and 3 of the drawings and is a conventional wire stitcher 60 which is supported from the end plate 6 on its outer side. A bracket 62 is mounted on the stitching machine and supports a reel 64 of wire. The wire is fed to the stitching machine from the reel as indicated at 66. The stitching machine includes a stitcher head 68 which periodically moves downwardly toward the anvil 70 (see Figs. 1 and 6) to form a wire stitch in the usual manner. Cam shaft 28 extends through the end plate 6 of the machine and is connected to the shaft of the stitching machine to drive the stitching machine.

Tag feeding means

The means whereby the tags are individually fed to the anvil 70 is shown in detail in Figs. 4, 5 and 7 to 14, inclusive. The tags are arranged in stacked relation in a tube 80 which is positioned adjacent the end plate 6. The detailed construction of the tag tube is shown in Figs. 17 to 20 and will be later described. Tags are

adapted to be taken from the lower end of the tube by a pair of gripping fingers 82 (see Fig. 10) and 84 (see Fig. 12). These gripping fingers are carried by a reciprocating member 86 (see Figs. 9 and 14) which reciprocates in a suitable guide-way 88 and cooperates with a second reciprocating member 90. These reciprocating members are actuated by cams 32 and 34. As shown, the cams are provided with grooves 92 and 94 adapted to receive rollers 96 and 98 carried by levers 100 and 102. The upper edge of the rear plate 8 of the frame of the machine is provided with a pair of slots or recesses 104 and 106. Plates 108 and 110 are secured to the rear plate 8 adjacent these slots. As shown the plates 108 and 110 are provided with elongated slots 112 for the reception of bolts passing through openings in the rear plate 8. The plates 108 and 110 are further provided with extensions 114 and 116 arranged over the slots 104 and 106 and levers 100 and 102 are pivotally mounted on bolts or pins 118 carried by these extensions. As shown the levers are provided with elongated slots 120. It will be apparent that the elongated slots 112 in the plates 108 and 110 and the elongated slots 120 in the levers 100 and 102 permit any desired adjustment of the throw of these levers. The lower end of lever 100 is connected to the reciprocating member 90 by a link 130 and the lower end of the lever 102 is similarly connected to the reciprocating member 86 by a link 132 (see Fig. 4).

The reciprocating members 86 and 90 are adapted to be moved from a position adjacent the lower end of tube 80 to a position adjacent the spider 134 (see Figs. 4, 5 and 7) to deliver a tag from the tube to a pair of jaws on one of the arms of the spider. In Fig. 4 the reciprocating members are shown at the outer end of the stroke. In Fig. 5, the full line position is at an intermediate point in the stroke and the position of the tag at each end of the stroke is shown in dotted lines. Gripping fingers 82 and 84 are adapted to be opened just prior to the inner end of the stroke to receive a tag from the bottom of the tube and at the outer end of the stroke after the tag has been gripped by the gripping fingers of the spider 134. The lower finger 84 is stationary and is mounted on the reciprocating member 86 by bolts or rivets which pass through the openings 136 in the finger. As shown the finger is substantially L-shaped and the gripping portion 138 is offset from the reciprocating member 86.

The end of the reciprocating member 86 is provided with a pair of sleeve-like members 140 separated from each other by a slot 142 (see Fig. 11). The finger 82 is carried by a similar sleeve-like body portion 143 having slots or cut-out portions 144 and the two parts are adapted to be assembled with the sleeve-like portions of one member received in the slots of the other member. These sleeve-like portions are provided with registering openings to receive a pivot pin 146. An arm 148 (see Fig. 14) is arranged on the body portion of finger 82 to cooperate with a cam carried by the reciprocating member 90 to open the gripping fingers at the inner end of the stroke and a similar arm 150 is carried by the finger 82 and projects in the opposite direction to cooperate with a second cam carried by the reciprocating member 90 to open the gripping fingers at the forward end of the stroke. The fingers are normally retained in closed position by a coil spring 152 (see Fig. 14) which is arranged in a bore 154 of the reciprocating member 86 and

which forces a pin 158 into a depression 160 in the adjacent portion of the finger 82. Finger 84 is provided with a recess 162 in its face and finger 82 is provided with a rib or extension 164 which cooperates therewith to insure a firm grip on the tag.

As stated, the cams for opening the gripping fingers are carried by the reciprocating member 90. One of these cams 166 is formed on a plate 168 on the top of the reciprocating member 90 (see Figs. 5 and 9) and is adapted to cooperate with a downwardly extending end 170 of the arm 148. The movement of the reciprocating members 86 and 90 is such that on the rearward stroke, movement of the reciprocating member 90 is arrested prior to movement of the reciprocating member 86 and arm 148 then rides upon the cam 166 to open the gripping fingers and engage a tag which has been projected from the bottom of the tube to the position C (Fig. 5).

A second cam is carried by the reciprocating member 90 and arm 150 is adapted to pass under this cam to swing the gripping fingers to an open position. As shown a plate 180 is arranged adjacent the outer end of the reciprocating member 90 (see Figs. 5 and 9) and this plate is provided with a cam surface 182 on its lower face. The arm 150 is provided with an upwardly extending portion 184 on its outer end which engages the cam surface 182, as shown in Fig. 9 of the drawings, to open the gripping fingers at the outer end of the stroke in position D (Fig. 5).

At the outer end of the stroke of the reciprocating members 86 and 90 the tag carried by the gripping fingers 82 and 84 is delivered to one of the arms of spider 134. This spider is driven with a step by step motion coordinated with the operation of the stitcher head by the shaft 40. As shown (see Fig. 7) the spider is mounted upon a shaft 200 supported in a suitable bearing 202 in the base of the machine and is provided with a spiral gear 204 on its lower end. Gear 204 meshes with a spiral gear 206 on shaft 40. The spider consists of a plurality of arms 210 which form the upper and stationary members of the gripping jaws which receive the tags from the gripping members 82 and 84. Each arm is provided with a pair of spaced downwardly extending portions 212 and a pivoted gripping member 214 is mounted on a pivot pin 216 carried by these downwardly extending portions. The gripping members are normally retained in closed position by means of springs 218 which are received in recesses in the upper and lower gripping members.

The jaws or gripping members 210 and 214 are opened at certain positions in the cycle of operation to receive a tag from the tag feeding mechanism and to release the tag after it has been stitched to the string of a bag. For this purpose I provide a cam 220 which is mounted on the shaft 200 preferably surrounding the hub 222 of the spider. The cam is provided with a high portion 224 throughout substantially half of its circumference and is adapted to be oscillated to open the gripping fingers just before they leave the position A in Fig. 4 of the drawings after the tag has been stitched to the bag string and to close them just before they leave the position B after they have received another tag. Cam 220 is provided with an arm 230 and a second arm 232 is secured thereto in the path of the reciprocating member 86. At the outer end of the stroke of reciprocating member 86, ears 140 engage the arm 232 to move the arm 230 and the cam in a

counterclockwise direction. The cam is returned to its normal position by means of a spring 234 which is secured to the outer end of the arm 230 and to a pin 236 mounted on the frame of the machine.

As shown in Fig. 8 of the drawings, the upper gripping members 210 of the spider are each provided with a depression or recess 238 and the lower gripping members are each provided with an extension or projection 240 registering with these recesses to assure a firm grip on the tag.

Tag delivery tube

Referring to Figs. 17 to 20, 22 and 23 of the drawings, the tags are stacked in tube 80, which is of an internal diameter substantially equal to the size of the tags and which is mounted on the machine in the position shown in Figs. 1, 4 and 5. The tube is supported by a pair of brackets 250 and 252 (see Fig. 1) carried by the end plate 6. The lower end of the tube is open at the front throughout substantially one-half of its diameter as shown at 254 (see Fig. 19) to permit the delivery of a tag. Adjacent the lower end the tube is surrounded by a collar 256. This collar, and the lower bracket 252 are provided with aligned openings for the reception of a rod 258. The lower end of this rod is offset into the open end of the tube and the face 260 of the offset portion is in line with the inside of the tube wall to engage the tags T at their circumferential edges. This rod is vertically positioned to engage the next to the bottom tag in the tube. Rod 258 is surrounded by a member 259 secured thereto by a set screw 261. A spring 263 is arranged in a recess in bracket 252, and surrounds rod 258. The lower end of this spring rests on member 259 to hold the rod in proper position. Tag engaging face 260 may be properly adjusted by set screw 261. The lower end of the front of the tube is provided with an opening 254 (see Fig. 19). The lower end of the back of the tube is provided with an opening 264 (see Figs. 19 and 20). An arm or projection 262 extends into the bottom of the tube at the back adjacent the opening 264. It is carried by a rod 270, the upper portion of which is clamped between the tube and the collar 256. The lower end of the collar is cut away at the rear as at 269 (see Figs. 20 and 23). The collar is also provided with an opening 271 at the front (see Fig. 18). At one side (see Fig. 22) the wall of the collar extends downwardly and is provided with an inclined lower edge 273. An arm or projection 267 extends from this side of the collar under the bottom of the tube to form a support for the tags (see Fig. 19). A similar arm or projection 265 extends from the other side wall of the bottom of the collar beneath the opening 271 (see Fig. 19). The arms or projections 262, 265 and 267 form supports for the column of tags arranged within the tube. Opening 271 in the front of the collar is of less diameter than the tags and is therefore not large enough to permit the delivery of a tag. Adjacent the arm or projection 265 the wall of the collar is slotted as at 275 (see Fig. 18) to provide an opening large enough for the delivery of a tag.

Means are provided for projecting the bottom tag in the tube partially from the tube to the position C shown in Fig. 5 of the drawings to permit it to be grasped by the gripping members 82 and 84. As shown (see Fig. 5) a reciprocating member 280 is mounted in a suitable guide or frame 282 on the frame of the machine. This

reciprocating member is of a proper size to enter the slots 264 and 269 and is bifurcated as at 284 to permit it to span the tag supporting arm 262. Adjacent its end it is decreased in thickness (see Fig. 5) forming shoulders 286 and when it reciprocates into the tube, the end portions 288 pass under the lower tag so that the tab is engaged by the shoulders 286 to move it outwardly to the position C. The reciprocating member 280 is actuated from the reciprocating member 86. As shown a link 290 is connected to the rear end of reciprocating member 280 by a pin 292, the pin being mounted on the reciprocating member 280 and being received in an elongated slot 294 in the link. The opposite end of the link 290 carries a pin 296 and this pin projects downwardly between a pair of arms 298 and 300 arranged on opposite ends of a plate 302 carried by the reciprocating member 86. As the reciprocating member 86 moves rearwardly or toward the tube, the arm 298 engages the pin 296 to swing the link in a clockwise direction and move the reciprocating member 280 into the bottom of the tube to project a tag to the position C. As the reciprocating member 86 moves forwardly, the arm 300 swings the link in the opposite direction to withdraw the reciprocating member 280 from the bottom of the tube and permit the next tag to move down in position to be fed from the tube. To insure rearward movement of the reciprocating member 280 a spring 304 is mounted on a rod 306 which is carried by the reciprocating member and which passes through an opening 308 in an arm or bracket carried by the guide 282. When the reciprocating member moves forwardly the spring is thus placed under tension.

To permit operation of the machine without delivering tags I provide means whereby the tags may be supported in a position above the bottom of the tube. A rod 320 is mounted in the rear of the tube and extends upwardly through openings in the brackets 250 and 252, the rod being provided with a handle 322 on its upper end to permit it to be lifted. As shown, this rod is arranged in alignment with the tag supporting arm 262 so that the bifurcated end 284 of the reciprocating member 280 may straddle it. The lower end of this arm carries a plate 324 which extends under the tube and is provided with upwardly extending arms 328 which engage the bottom tag of the stack adjacent the arm 262. By lifting the handle 322 the entire assembly may be moved upwardly to bring the bottom tag out of the plane of the reciprocating member 280 and thus prevent delivery of a tag from the tube.

Bag feeding means

A stated, the stitching machine is preferably used in conjunction with a standard tobacco filling machine and is arranged adjacent the outlet of the tobacco filling machine so that the filled bags to which the labels and revenue stamps have been applied are delivered to the stitching machine. The bags are delivered to a platform 350 which extends across the front of the machine adjacent the anvil of the stitcher and which may be provided with an inclined portion 352 adjacent the anvil (see Fig. 3). The platform is of a width substantially equal to the length or height of a bag R and is provided with a vertical wall or flange 354 at each side throughout the greater portion of its length. The bags are fed to the platform with the strings S depending from the side adjacent the anvil (see Figs. 3 and 6) and are fed along this platform

by means of a suitable pushing device (not shown) which forms a part of the discharge mechanism of the tobacco filling machine and pushes the bags along the platform toward the anvil. Adjacent the anvil the platform is provided with a horizontal portion 356 and as the bags are pushed from the end of this horizontal portion they may fall upon a downwardly inclined platform 358 over which they are fed to a suitable receptacle. Adjacent the anvil the flange 354 is eliminated on the side of the platform toward the anvil providing an opening as indicated at 360 (see Figs. 4 and 5). Beyond the opening 360 the flange is flattened as at 361 for a slight distance. Means are provided for engaging the bag that is positioned in front of the anvil and to which a tag is being applied to hold it in position during the stitching operation. As shown an arm 362 is secured to a post 363 adjacent the stitcher head and is provided with an offset portion 364 to position the end of the arm transversely over the platform 350. As shown in Fig. 3 of the drawings the end of the arm 362 is positioned over the horizontal portion of the platform and spaced from it a distance substantially equal to the thickness of a bag.

A reciprocating and oscillating hook is adapted to engage one of the strings S of the bag and deliver it to a position over the anvil for the stitching operation. The hook 366 (see Fig. 5) is pivotally mounted upon the end of a reciprocating member 368. This reciprocating member cooperates with a second reciprocating member 370, the members reciprocating in a suitable guide or frame 372 on the frame of the machine. Pins 374 and 376 are carried by these members adjacent their rear ends and these pins receive the ends of levers 378 and 380 respectively. Levers 378 and 380 are provided with rollers 382 and 384 respectively which ride in cam grooves 386 and 388 formed in cams 36 and 38 respectively. These levers are pivoted to the back wall of the machine in a manner similar to the levers 108 and 102. As shown, each lever is provided with an elongated slot 387 for the reception of a pivot 389 and the pivot pins are carried in plates 390 which are secured to the rear wall 8 by suitable bolts 392 or other fastening means. The plates are provided with elongated slots 394 to permit adjustment and the rear wall 8 is provided with slots 396 adjacent the points where the levers 378 and 380 are pivoted.

To impart a reciprocating and oscillating motion to the hook by the reciprocation of the members 368 and 370, I provide an arm 400 adjacent the end of the reciprocating member 368 and a substantially L-shaped lever 402 is pivoted on this arm by a pivot pin 404. The hook 366 is secured to this L-shaped member. The reciprocating member 370 is provided with a slot 406 which receives a pin 408 carried by the lever 402.

When the hook 366 is in the position shown in Fig. 4 of the drawings and is about to be reciprocated inwardly toward the anvil, the string S of the bag is over the end of the hook and as the hook moves inwardly it engages knot 410 in the string which prevents further movement of the string over the hook. In front of the anvil I provide a guideway or platform 412 on which is formed a groove 414 (see Figs. 5 and 15) which groove converges inwardly toward the anvil and through which the bag string is carried by the hook to the position over the anvil shown in Fig. 5 of the drawings. An arm 415, preferably in the form of a thin sheet metal member, is secured to

the post 363 (see Fig. 3) and extends substantially parallel to the edge of the platform. This arm is provided with a notch 416 arranged adjacent the end of the opening 360 (see Figs. 6 and 16). As the hook moves from the position shown in Fig. 4 of the drawings and engages the bag string, the end of the bag is positioned against the arm 415 and the string enters the notch 416 (as shown in Fig. 16 of the drawings). As the string S is fed to the anvil, the arm 415 removes the pull of the hook from the bag and prevents damage to the revenue stamp or label on the bag. As the string is passing through the groove 414 it passes under a combing device 420 (see Figs. 5, 15 and 16) which is preferably a piece of felt secured to the front of the machine and which combs out the bag string. After the bag string has been stitched to the tag as indicated at W in Fig. 21 of the drawings, the bag passes on to the inclined platform 358.

I further provide a guide or plate 470 which is arranged over the platform (see Fig. 3) and spaced from it a distance equal to the thickness of a bag. This plate has a depending flange 472 which engages the bags and prevents them from buckling as they are pushed along the platform by the pushing device. Above the flange the plate is provided with an inwardly extending portion 474 and a vertical portion 476 which is bolted to the post 363.

I further provide means for stopping the machine upon failure of the delivery of tags. A casting 430 is arranged on the bed 2 of the machine (see Figs. 1 and 5) at the next position of the spider 134 after it receives a tag from the fingers 82 and 84. This casting is provided with an opening or depression and an arm 432 extends over the casting and is provided with an end portion in alignment with the depression. Arm or lever 432 is pivotally mounted on a bracket 434 on the frame of the machine (see Fig. 4) and is provided with an offset rear end 436. The offset end of this arm is adapted to contact with a cam 438 mounted on the shaft 12. The arm is also connected to a rod 440 which extends through a suitable opening in the bed 2 of the machine. A spring 442 is arranged on this rod and engages the bed of the machine to normally move this rod upwardly. An operating arm 444 is carried by the rod 440 beneath the bed of the machine and is adapted to engage a switch 446 of the push button type when the arm moves upwardly to operate the switch and stop the machine. The arm or lever 432 is also provided with a handle 448 (see Figs. 1 and 4) which may be manually actuated to operate the switch 446.

Drive shaft 12 is provided with a second cam 450 which engages a link 452. Link 452 is connected to a lever 454 pivotally mounted in a suitable support on the under side of the bed 2 of the machine. The free end of lever 454 carries an adjustable screw 456 which extends through a bore in a plate 460 on which the anvil 70 is mounted. The body of the anvil 70 is provided with a bore for the reception of a movable member 458 which forms a part of the anvil. This member causes the wire to be flattened on the tag and eliminates the possibility of projecting ends which might cause tangles between the strings of adjacent bags. A plate 459 is mounted upon this movable member of the anvil 70 in contact with the end of screw 456. A spring 462 is arranged in a bore in the body of the casting 500 which carries the anvil. The lower end of this bore is enlarged to receive the plate 459. Spring 462 engages this plate to retain the mem-

ber 459 in lowered position except when it is projected upwardly by the screw 456. A nut 470 may be arranged on the screw 456 as shown.

General operation of the machine

In operation cam shaft 28 is driven from main shaft 12 in the manner heretofore described and the reciprocating members 86 and 90 of the tag feeding mechanism and reciprocating members 368 and 370 which reciprocate and oscillate the hook are driven from this shaft by means of cams 32, 34, 36 and 38. At the same time a step by step movement is imparted to the spider 134 through the Geneva gearing and shaft 40. Bags are delivered to the platform 350 from the tobacco filling machine (not shown) and as each bag is delivered to the inlet end of this platform the preceding bags are pushed forwardly toward the anvil as shown in Fig. 3 of the drawings. Plate 470 extends over the edge of the platform as shown in Fig. 4 and the flange 472 engages the tops of two or more bags as shown in Fig. 3 to retain the bags in a flat position on the platform 350. As the bags are fed upwardly toward the horizontal portion of the platform, they pass under the arm 362 which holds each bag during the stitching period. The notch 416 in the arm 415 receives the bag string as the string is being fed through the groove 414 toward the anvil as shown in Figs. 5 and 6 and the end of the bag positioned against the arm 415 prevents injury to the revenue stamp and label on the bag.

When the reciprocating members 86 and 90 move rearwardly the member 90 is stopped first and as the member 86 reaches the rear end of its stroke, finger 148 rides over the cam 166 to open the fingers and permit them to grasp a tag in position C in Fig. 5 of the drawings. Reciprocating member 90 then moves further rearwardly to close the fingers 82 and 84 and the forward stroke then carries a tag which has previously been ejected to the position C by the member 280 to a position to be grasped by a pair of fingers on one arm of the spider 134. At the position B shown in Fig. 4 of the drawings the forward movement of the member 90 first stops and member 86 moves further forwardly until the arm 150 passes under the cam 182 to open the fingers 82 and 84.

In the meantime the fingers 210 and 214 of the arm of the spider in this position have been opened by the cam 220 and upon closure of these fingers the tag is grasped and carried by the spider in its step by step movement to the anvil.

During the movement of the spider to its next position over the casting 430, arm 432 is rocked by cam 438 to raise the end of the arm and permit the tag to pass under it. As soon as the high point of the cam passes from the offset end 436 of the arm or lever 432, spring 442 tends to raise the rear end of this lever and depress its forward end. This movement is arrested by a tag in the arm of the spider, but if no tag has been fed, the forward end of lever 432 is free to move downwardly raising rod 440 and causing the arm 444 to operate the switch and shut off the power from the machine.

Assuming that a tag has been properly delivered to the arm of the spider, the spider proceeds through two more positions to deliver the tag to the anvil. The movement of the spider is coordinated with the movement of the stitcher head so that one of the arms will position a tag over the anvil prior to each descent of the stitcher head. The string S having also been

fed to position shown in Fig. 5 of the drawings, the stitcher head descends and a wire stitch W secures the tag to the string.

Arm 363 holds the bag in place during the stitching operation and arm 415 holds the bag string between it and the platform 412 as shown in Fig. 16 of the drawings so that the pull of the hook 366 is not transmitted along the string beyond this point of engagement and damage to the revenue stamp or label is thus prevented.

The height of the side walls 354 of the platform 350 is such that the knotted portion of the bag string at the mouth of the bag is just above it and the bag string hangs over this wall. With the hook in the dotted line position shown in Fig. 5 of the drawings simultaneous forward reciprocation of the members 368 and 370 moves the hook outwardly toward the platform 352. After the hook has been moved outwardly the member 368 is stopped. Member 370 travels a further distance to oscillate the hook in a clockwise direction on its pivot 404. This moves the hook across the front of the machine causing it to engage the string S (see Fig. 4). The two reciprocating members 368 and 370 then move rearwardly, causing the hook to move inwardly toward the anvil to the full line position shown in Fig. 5. During this movement the string is over the hook and slides over it for a distance until the knot 410 in the groove 414 prevents further relative movement of the string and the hook and the string is then carried inwardly. The stitcher head then descends and the hook is then moved out of the loop in the string from the full line position shown in Fig. 5 of the drawings to the dotted line position by rearward movement of the reciprocating member 370 while the reciprocating member 368 is stationary which again causes the hook to swing on its pivot 404 in the opposite direction from its previous oscillation. The gripping fingers of the spider are held in closed position from a time just after the reception of the tag until after the tag has been stitched to the bag string at the position A. Between the position A and the following position the gripping fingers are opened by the oscillation of cam 226 to release the tag which has been stitched to the string. The bag is further propelled across the horizontal portion 356 of the platform to the inclined platform 358 (see Fig. 5). In case of a failure of the stitching operation, the loose tag drops on to a platform 357 which conveys it to any suitable receptacle and the bag to which a tag has not been stitched will later be removed from the stitched bags by an inspector.

The operation of the member 280 to partially project a tag to the position C in Fig. 5 of the drawings will be apparent from the previous description. Cam 450 oscillating the link 452 and the lever 454 moves the movable member 458 of the anvil upwardly into operative position at each stroke of the stitcher head to produce a flat stitch with no projecting wire ends and thus prevent subsequent entangling of the strings and tags on adjacent bags.

I claim:

1. In combination with a wire stitcher, means for stitching a tag to one of the strings of a bag of the string closure type, said means comprising a platform over which the bags are propelled to a point adjacent the anvil of the stitcher, means for delivering tags to the anvil of the stitcher, an oscillating and reciprocating hook to guide one of the bag strings over the anvil, a cam shaft,

and cams mounted on the cam shaft to actuate the tag feeding means and the hook from the cam shaft.

2. In combination with a wire stitcher, means for stitching a tag to one of the strings of a bag of the string closure type, said means comprising a channel shaped platform extending in front of the anvil in close proximity thereto over which the bags are propelled to a position adjacent the anvil, means for guiding one of the strings of the bag on the platform over the anvil, and means for feeding a tag to the anvil to be stitched to the bag string.

3. In combination with a wire stitcher, means for stitching a tag to one of the strings of a bag of the string closure type, said means comprising a channel shaped platform extending in front of the anvil over which the bags are propelled to a position adjacent the anvil, means for guiding one of the strings of the bag on the platform over the anvil, means for feeding a tag to the anvil to be stitched to the bag string, a cam shaft, and cams mounted on the shaft to drive the tag feeding means and the string guiding means.

4. In combination with a wire stitcher, means for stitching a tag to one of the strings of a bag of the string closure type, said means comprising a platform over which the bags are propelled to a position adjacent the anvil, means for holding the bag in place on the platform during the stitching operation, said means comprising an arm spaced from the platform, and a second arm arranged adjacent the side of the platform and engaging the bag string.

5. In combination with a wire stitcher, means for stitching a tag to one of the strings of a bag of the string closure type, said means comprising a platform having side walls extending in front of the anvil in close proximity thereto over which the bags are propelled to a position adjacent the anvil, the wall of the side of the platform adjacent the anvil being cut away, and means for feeding the string of a bag over the anvil while the bag is on the platform.

6. In combination with a wire stitcher, means for stitching a tag to one of the strings of a bag of the string closure type, said means comprising a platform over which the bags are propelled to a position adjacent the anvil of the stitching machine, a tube to receive tags in stacked relation, means for feeding single tags from the tube to the anvil, said means comprising a pair of reciprocating members, one of which is provided with tag engaging fingers to receive a tag from the tube, a spider having a step by step movement coordinated with the stitcher head and having tag engaging fingers on each of its arms adapted to receive tags from the tag engaging fingers of the reciprocating member, a hook to guide the bag string over the anvil, a pair of reciprocating members to reciprocate and oscillate the hook, a cam shaft, and cams mounted on the shaft and driving said reciprocating members.

7. In combination with a wire stitcher, means for stitching a tag to one of the strings of a bag of the string closure type, said means comprising a platform over which the bags are propelled to a position adjacent the anvil of the stitching machine, a tube to receive the tags in stacked relation, means for feeding single tags from the tube to the anvil, said means comprising a pair of reciprocating members, tag engaging fingers carried by one of the reciprocating members, a hook to guide the bag string over the anvil, a pair of reciprocating members to recip-

rotate and oscillate the hook, a cam shaft, and cams on said shaft to drive said reciprocating members.

8. In combination with a wire stitcher, means for stitching a tag to one of the strings of a bag of the string closure type, said means comprising a platform over which the bags are propelled to a position adjacent the anvil of the stitching machine, a tube to receive the tags in stacked relation, means for feeding single tags from the tube to the anvil, said means comprising a pair of reciprocating members, tag engaging fingers carried by one of the reciprocating members, means for guiding the bag string over the anvil, a cam shaft, and cams on the shaft to actuate the string guiding means.

9. In combination with a wire stitcher, means for stitching a tag to one of the strings of a bag of the string closure type, said means comprising a platform over which the bags are propelled to a position adjacent the anvil of the stitching machine, means for feeding tags to the anvil of the stitching machine, a hook to guide the bag string over the anvil, a pair of reciprocating members to oscillate and reciprocate the hook, a cam shaft, and cams mounted on the shaft to drive the reciprocating members.

10. In combination with a wire stitcher, means for stitching a tag to one of the strings of a bag of the string closure type, said means comprising a platform extending in front of the anvil in close proximity thereto over which the bags are propelled to a position adjacent the anvil, a tube to receive tags in stacked relation, means for feeding individual tags from the tube to the anvil, a hook to guide the bag string over the anvil, and a pair of reciprocating members to oscillate and reciprocate the hook.

11. In combination with a wire stitcher, means for stitching a tag to one of the strings of a bag of the string closure type, said means comprising a platform extending in front of the anvil in close proximity thereto over which the bags are propelled to a position adjacent the anvil, a tube to receive the tags in stacked relation, means for feeding single tags from the tube to the anvil, said means comprising a pair of reciprocating members, one of which is provided with tag engaging fingers to receive a tag from the tube, a hook to guide the bag string over the anvil, and a pair of reciprocating members to oscillate and reciprocate the hook.

12. In combination with a wire stitcher, means for stitching a tag to one of the strings of a bag of the string closure type, said means comprising a platform over which the bags are propelled to a position adjacent the anvil, a tube to receive tags in stacked relation, means for feeding individual tags from the tube to the anvil, a hook to guide the bag string over the anvil, a pair of reciprocating members to oscillate and reciprocate the hook, a cam shaft, and cams carried on the shaft and connected to the reciprocating members to actuate them.

13. In combination with a wire stitcher, means for stitching a tag to one of the strings of a bag of the string closure type, said means comprising a platform over which the bags are propelled to a position adjacent the anvil, a tube to receive tags in stacked relation, means for feeding individual tags from the tube to the anvil, a hook to guide the bag string over the anvil, a pair of reciprocating members to oscillate and reciprocate the hook, and an arm arranged adjacent the side of the platform at the point where the

string is guided over the anvil and adapted to engage the string as it is fed toward the anvil.

14. In combination with a wire stitcher, means for stitching a tag to one of the strings of a bag of the string closure type, said means comprising a platform extending in front of the anvil in close proximity thereto over which bags are propelled to a position adjacent the anvil of the stitching machine, means for feeding individual tags to the anvil of the stitching machine, a hook to guide one of the bag strings over the anvil, a pair of reciprocating members associated with the hook, the hook being pivoted to one of said members, and a connection between said members to oscillate the hook.

15. In combination with a wire stitcher, means for stitching a tag to one of the strings of a bag of the string closure type, said means comprising a platform over which the bags are propelled to a position adjacent the anvil of the stitching machine, means for feeding individual tags to the anvil of the stitching machine, a hook to guide one of the bag strings over the anvil, a pair of reciprocating members associated with the hook, the hook being pivoted to one of said members, one of said reciprocating members being provided with an elongated slot, and a pin carried by the hook and received in said slot to oscillate and reciprocate the hook upon reciprocation of said members.

16. In combination with a wire stitcher, means for stitching a tag to one of the strings of a bag of the string closure type, said means comprising a platform extending in front of the anvil in close proximity thereto over which the bags are propelled to a position adjacent the anvil, a tube to receive tags in stacked relation, means for feeding individual tags from the tube to the anvil, a hook to guide a bag string over the anvil, and a pair of reciprocating members to oscillate and reciprocate said hook.

17. In combination with a wire stitcher, means for stitching a tag to one of the strings of a bag of the string closure type, said means comprising a platform over which the bags are propelled to a position adjacent the anvil, a tube to receive tags in stacked relation, means for feeding individual tags from the tube to the anvil, a hook to guide a bag string over the anvil, a pair of reciprocating members to oscillate and reciprocate said hook, and an arm adjacent one side of the platform, said arm being adapted to engage the bag string being guided over the anvil.

18. In combination with a wire stitcher, means for stitching a tag to one of the strings of a bag of the string closure type, said means comprising a platform extending in front of the anvil in close proximity thereto over which the bags are propelled to a position adjacent the anvil, a tube to receive tags in stacked relation, means for feeding individual tags from the tube to the anvil, a hook to guide the bag string over the anvil, and an arm arranged over the platform and engaging the bag when in one position to hold the bag in position on the platform.

19. In combination with a wire stitcher, means for stitching a tag to one of the strings of a bag of the string closure type, said means comprising a platform over which the bags are propelled to a position adjacent the anvil of the stitching machine, means for feeding individual tags to the anvil of the stitching machine, a hook to guide one of the bag strings over the anvil, a pair of reciprocating members associated with the hook, the hook being pivoted to one of said members,

a connection between said members to oscillate the hook, an arm arranged over the platform and adapted to engage a bag when in one position, and a second arm arranged adjacent the side of the platform and adapted to engage the bag string while the string is being guided over the anvil.

20. In combination with a wire stitcher, means for stitching a tag to one of the strings of a bag of the string closure type, said means comprising a channel shaped platform extending in front of and in close proximity to the anvil over which the bags are propelled to a position adjacent the anvil, means for guiding one of the strings of the bag on the platform over the anvil while the bag is on the platform, means for feeding a tag to the anvil to be stitched to the bag string, and an arm engaging the bag to hold it in position while the bag string is being guided over the anvil.

21. In combination with a wire stitcher, means for stitching a tag to one of the strings of a bag

of the string closure type, said means comprising a platform extending in front of the anvil in close proximity thereto over which the bags are propelled to a position adjacent the anvil, means 5 for holding the bag in place on the platform during the stitching operation, said means comprising an arm arranged over the platform, and a hook to engage the bag string and guide it over the anvil.

10 22. In combination with a wire stitcher, means for stitching a tag to one of the strings of a bag of the string closure type, said means comprising a platform extending in front of the anvil in close proximity thereto over which the bags are 15 propelled to a position adjacent the anvil, means for holding the bag in place on the platform during the stitching operation, said means comprising an arm arranged over the platform, a hook to engage the bag string and guide it over the anvil, and a pair of reciprocating members to oscillate and reciprocate the hook.

JOHN THOMAS DALTON.
